UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

BRAKE.

Application filed August 30, 1926. Serial No. 132,482.

This invention relates to brakes.

An object of the invention is to provide a brake for railway and other vehicles having means for quickly taking up the slack of the 5 brake chain, and thereafter automatically increasing the leverage ratio pull on the brake chain during the final application of the braking pressure.

Another object of the invention is to provide 10 a power increasing device of this character, comprising lever means connected with the brake rigging in such manner that during the initial application of power to the brake rigging, the lever means travel in inoperative position, and when the tension is increased 15 on the rigging so as to initiate swinging movement of the lever means, portions of the brake rigging engage the lever means to provide a fixed fulcrum therefor, automatically putting 20 into action the power multiplying effect of the arms of the lever. The parts are arranged so that upon the release of the brake rigging they will automatically resume their original 25 positions.

Other and further objects of the invention will more fully and clearly appear from the description and claims hereinafter following.

Figure 1 is a fragmentary side elevational view of a railway car having a brake winding 30 mechanism, and showing my invention used in connection therewith, the parts being shown in fully released position. Figure 2 is a top plan, part-sectional view, corresponding substantially to the line 2-2 of Figure 1; and 35 Figure 3 is a part sectional, part elevational view of the invention taken on the line 3-3 of Figure 1.

In the drawings, 10 represents a fragment 40 of a railway car, 11 a supporting bracket, 12 a brake winding staff, 13 a ratchet mechanism for preventing retrograde rotation of the staff 12, and 14 the usual brake supporting stirrup for the lower end of the brake staff.

The invention broadly includes guiding 45 means A, power multiplying means B, lever operating rigging C, and connecting means D leading to the brake shoes proper.

The guide means A comprise suitably 50 spaced longitudinally extending supporting rails or bars 15-15, each of which is provided with angular sections 16-16 at its opposite

ends, which have their free ends secured to the under surface of the car structure by rivets or other suitable securing means indicated at 17.

The lever means comprise a pair of spaced 55 lever arms 18-18, said arms being connected together by means of a semi-circular engaging hub 19, which has semi-circular flanges 20-20 at its ends, and which also has an integral radially extending web 21, as shown in Figure 3, which is provided with a centrally arranged notch 22 for co-operation with an element of the brake rigging as hereinafter described. The lever means is provided with 60 trunnions 220-220 located substantially coaxially with respect to the center of the bearing portion 19, the lever means being disposed between the rails 15-15, and the trunnions 220-220 resting upon the top edges of said 65 rails as best shown in Figure 3, said trunnions providing a support having slid able engagement with the top edges of the rails 15-15. The bifurcated ends of the lever means are provided with a pin which projects 70 outwardly as indicated at 24, the ends of said pin being adapted to rest upon the top edges of the rails 15-15. Between the arms of the lever, upon the pin 24, there is rotatably mounted a sheave 25, adapted to accommodate 75 the brake chain. The brake rigging C comprises a brake chain indicated at 27, having one end connected to the brake staff 12 at a point spaced upwardly from its lower end as indicated at 28, said chain extending toward 80 the sheave 25, being looped over said sheave and extending by means of the leg 128 to the lower end of the brake staff 12 or its supporting step, to avoid friction.

Co-operating with the lever means 18-18 90 are connecting links 29-29, each of which has one end mounted upon a pin 30, carried by said lever means adjacent the trunnions 220-220, and disposed somewhat to one side of the longitudinal center line of the lever 95 means, as shown. The intermediate portions of the links 29-29 are cut out as indicated at 31, so that when the links are in a substantially horizontal position they provide room 100 to permit bearing of the ends of the pin 24 upon the top surfaces of the rails 15-15. The free ends of the links 29-29 have a pin

32 extending therethrough, and between the ends of said links upon said pin, there is pivotally mounted the connecting member D, which has an extension 34 which is connected 5 with the brake shoes proper. In order to maintain the power multiplying mechanism in assembled relation with the rails or guides 15—15, keepers 35—35 in the form of bars are secured to the uprights 16—16 at one side 10 of the rails 15—15 and slightly above the trunnions provided by the pins 23 and 32, so that the device is maintained at all times in assembled relation with the rails and the lever means are free to operate in the desired manner. 15

In operation, upon clockwise rotation of the staff 12, the leg 27 of the brake chain is wound upon the brake staff, causing travel 20 of the rigging C as permitted by the sheave 25, causing the lever means to travel in a horizontal position toward the staff 12 due to the fact that in taking up of the slack there is relatively little resistance encountered in the brake rigging. The movement of the lever means is transmitted through the medium of 25 the links 29—29, and the connecting member 34, to the brake shoes proper. When increased resistance is encountered in the brake rigging, due to the engagement of the brake shoes with the wheels, the increase in resistance causes the lever means to swing upwardly from the position shown in Fig. 1 in a clockwise direction toward the brake staff 12. This movement of the lever means elevates the leg 128 of the brake chain, causing the same to move into the notch 22 formed in the bearing portion 19, thereby arresting the sliding movement of the lever means toward the staff 12, so that further taking up of the brake 40 chain swings the lever means about a relatively fixed fulcrum point with a consequent great increase in the power ratio, the power being transmitted through the links 29—29 to the brake shoes proper. 45

Upon the release of the braking rigging by the unwinding of the brake staff, the lever means are drawn to the original position causing release of the leg 128 of the brake chain, so that the mechanism resumes its position for 50 another operation.

While I have herein shown and described what I now consider the preferred manner in carrying out my invention, the same is merely illustrative and I contemplate all 55 changes and modifications that come within the scope of the claims appended hereto.

I claim:

1. In a brake, the combination with a brake staff; of supporting means secured to the car 60 structure; of lever means adapted to swing about one end as a fulcrum, said fulcrum end being provided with trunnion elements and a holding element, and the opposite end of said lever means having a sheave mounted thereon; link means pivotally connected to said

lever means intermediate the ends of the latter, and the opposite end of said link means being connected with the brake shoes proper, said opposite end having trunnion elements associated therewith, all of said trunnion elements bearing on and being movable with respect to said supporting means; and retaining elements cooperating with said supporting means for confining said trunnions to movement in a predetermined path; and a 70 double ended chain connected to said staff and having an intermediate portion looped over said sheave, one end portion of said chain extending in proximity to the holding element on said lever means and adapted to be 75 engaged thereby in certain positions of the parts. 80

2. In a brake, the combination with a brake staff; of lever means adapted to swing about one end as a fulcrum, said fulcrum end having a holding element connected therewith and the opposite end of said lever means carrying a rotatable sheave, link means connected at one end to said lever means, and at the opposite end adapted to be connected to the brake shoes proper; a double ended chain having one end connected to said staff and the other end fixed and having an intermediate portion looped over said sheave, one end portion of said chain extending in proximity to said holding element on said lever means and adapted to be engaged thereby in certain positions of the parts; and means for confining the fulcrum end of said lever means and the end of said link means remote from said lever means, to movement in predetermined positions. 90

3. In a brake, the combination with a winding staff; of lever means adapted to swing about one end as a fulcrum, said fulcrum end being notched, and the opposite end of said lever means being provided with a rotatable sheave; a double ended brake chain composed of a plurality of connected links providing abutment projections at opposite ends of each connected link, said chain having one end connected to said winding staff and the opposite end fixed, an intermediate portion of said chain being looped over said sheave, and one end portion of said chain extending in proximity to the notch of said lever means and adapted to have one of the links disposed therein when the lever is swung toward a vertical direction with the adjacent link in abutment with the lever; and means 110 adapted to connect said lever means to the brake shoes proper. 115

4. In a brake mechanism, the combination with an operating member for taking up a chain; of a chain connected at one end to 120 said operating member and having the other end fixed; a power-multiplying mechanism, including a lever having said chain trained thereabout; a link pivoted to said lever adjacent one end thereof, said last named end of 130

the lever interlocking with the chain when the lever is swung on said pivot to compel said end of the lever to fulcrum on the chain, said link being operatively connected to the brake 5 shoes of the brake mechanism proper; and means for guiding the connected pivotal portion of the lever and link and the opposite end

portion of the link for movement in the same fixed path.

In witness that I claim the foregoing I have 10 hereunto subscribed my name this 19th day of August, 1926.

JOHN F. O'CONNOR.
